United States Patent Office

Des. 202,299
Patented Sept. 14, 1965

202,299

BOTTLE

Leonard M. De Karr, San Marino, Calif., assignor to Brunswig Drug Company, Los Angeles, Calif., a corporation of California

Filed July 15, 1964, Ser. No. 80,882

Term of patent 14 years

(Cl. D58—8)

FIG. 1.

FIG. 2.

FIG. 3.

FIG. 5.

FIG. 4.

I claim:

An ornamented design for a bottle, substantially as shown.
